[57] CLAIM

The ornamental design for an external connector for a portable communication device, as shown and described.

DESCRIPTION

FIG. 1 is a top, front, and right side isometric view of an external connector for a portable communication device showing my new design;

FIG. 2 is a front elevational view thereof;

FIG. 3 is a rear elevational view thereof;

FIG. 4 is a bottom plan view thereof;

FIG. 5 is a left side elevational view thereof;

FIG. 6 is a right side elevational view thereof;

FIG. 7 is a top plan view thereof; and,

FIG. 8 is a top, rear, and right side isometric view thereof.

The broken lines shown in FIGS. 1, 4, 6, 7, and 8 are included for the purpose of illustrating environmental elements only and form no part of the claimed design.
